UNITED STATES PATENT OFFICE.

SAMUEL HAYWARD, OF BOSTON, MASSACHUSETTS, ASSIGNOR TO J. ESTEY & COMPANY, OF BRATTLEBOROUGH, VERMONT.

DESIGN FOR AN ORGAN-CASE.

Specification forming part of Design No. 6,510, dated March 18, 1873.

To all whom it may concern:

Be it known that I, SAMUEL HAYWARD, of Boston, in the State of Massachusetts, have invented a Design for an Organ-Case, of which the following is a specification:

In the accompanying photographic illustration, to which reference is made, my design is fully represented; and it consists in forming the case with a contracted top, and with ornamental handles at the end of the case.

A represents the contracted top, and E the ornamental handles. The contracted top A surmounts the case and is formed of a size less than the ordinary top, the diminution being equal on all sides. The contracted portion rises to a slight elevation above the general surface of the top, and is preferably molded to break the abrupt angles and give an agreeable finish and appearance. This contracted top surmounting the case, and, simple in its general form, gives a novel, neat, and ornamental appearance to the general design

of the case. The handles B are situated at the ends of the case and a little distance below the cornice or top ornament, or projection C, and nearly on a level with the keyboard of the instrument. These handles project considerably from the plane of the end of the case, and may be finished with more or less ornamentation, imparting to it a bold, pleasing, and effective appearance, relieving the ordinary plainness of this part of an organ-case.

I claim as my invention—

1. The design for the top A of the case, substantially as herein shown.
2. The design for the handles upon the ends of the case, as herein shown and described.

In witness whereof I have hereunto signed my name in the presence of two subscribing witnesses.

Witnesses: SAMUEL HAYWARD.
